UNITED STATES PATENT OFFICE.

HORACE DAVIS BUCK, OF NEW YORK, N. Y.

KNITTING-MACHINE ATTACHMENT.

1,058,543.

Specification of Letters Patent.

Patented Apr. 8, 1913.

Application filed April 15, 1911. Serial No. 621,217.

To all whom it may concern:

Be it known that I, HORACE D. BUCK, a citizen of the United States, and a resident of the city of New York, borough of Brooklyn, in the county of Kings and State of New York, have invented a new and Improved Knitting-Machine Attachment, of which the following is a full, clear, and exact description.

10 This invention relates to a new and improved attachment for knitting machines of a type adapted to knit sweaters, whereby the speed thereof may be varied to allow for different conditions, such as knitting 15 plain or half-cardigan and racking stitches.

In many types of sweaters, it is often desirable to knit a band adjacent the lower end thereof, of a racking stitch, while the remainder has a plain stitch. In such an 20 event, it has been found in practice that while knitting this racking stitch, the machine must be run much slower than is necessary when knitting the plain stitch. As far as I am aware, such machines as are now 25 on the market run at the slow speed at all times, so as to accommodate the racking stitch, and thus waste considerable time, when they might be running fast while making the plain stitch. Inasmuch as the plain 30 stitch is used in the greater part of the sweater, a considerable loss in time and capacity is evident.

It is therefore an object of this invention to provide an attachment for a knitting machine, which will automatically shift from 35 a fast speed while knitting the plain stitch, to a slow speed while knitting the racking stitch, and also automatically shift back from a slow speed to a high speed when 40 changing from the racking stitch to the plain stitch.

A further object of this invention is to provide a device which will be simple in construction, inexpensive to manufacture, 45 strong, durable, readily accessible and adjustable, and automatic in its operation.

These and further objects, together with the construction and combination of parts, will be more fully described hereinafter and 50 particularly set forth in the claims.

Reference is to be had to the accompanying drawings forming a part of this specification, in which similar characters of reference indicate corresponding parts in all 55 the views, and in which—

Figure 1 is a diagrammatic horizontal sec-

tional view, showing the arrangement of the more important parts of this attachment; Fig. 2 is a vertical section on the line 2—2 of Fig. 1; Fig. 3 is a fragmentary side view in elevation; Fig. 4 is a detail view of the mechanism for controlling the shift from one speed to another, operated from the knitting-mechanism control; and Fig. 5 is a perspective view in elevation.

Referring more particularly to the separate parts of this invention as embodied in the form shown in the drawings, 1 indicates the driving shaft, which may be driven in any suitable manner from any suitable source of power, as for example by being provided with a tight pulley 2 and a loose pulley 3 driven by a shiftable belt. On the shaft 1, there are fixed a plurality of gears 4 and 5 of different diameters and having different numbers of teeth, so as to afford a different driving ratio. The gear 4, which is shown as the largest, meshes with a gear 6 loosely mounted on a shaft 7. The gear 5 meshes with a gear 8, which is also loosely mounted on the shaft 7 and separate from the gear 6. It will be seen that if the drive from the shaft 1 to the shaft 7 is through the gears 4 and 6, the shaft 7 will be driven at a greater speed than if it were driven through the gears 5 and 8. In order to connect either of the gears 6 or 8 to the shaft 7, there is provided a key 9, which is slidably mounted in a spline in the shaft 7 and in a collar 107, secured to the shaft 7 by a pin 108. This key can be moved to a position such that it will connect either of the gears 6 and 8 to the shaft 7, in which position it will rotate with the collar 107 in a cavity 10 formed by facing cavities provided in the opposed sides of the gears 6 and 8. Each of these cavities, however, has grooves or recesses 11 and 12 communicating therewith, whereby the key can be locked to either of the gears, thus securing either of the gears to the shaft 7. The key 9 is connected by a rod 13, which extends in a groove in the shaft 7, to a collar 14. The collar 14 is of the grooved type, and may be operated in a manner to be described. On the shaft 7, there is provided a bevel gear 15, which meshes with a bevel gear 16 on a table 17. This table is part of the knitting mechanism, and is rotated from the shaft 7 by this connection. The shaft 7 is also provided with a bevel gear 18, which meshes with a corresponding bevel gear 19.

on another part 20 of the knitting mechanism. The knitting mechanism is thus also operated from the shaft 7, and its speed depends on the speed of the shaft 7.

It will be readily understood by those skilled in the art that the parts enumerated above are supported upon a suitable framework; a part of this framework is shown in Fig. 1, and comprises a pair of standards *a* carrying alined bearings to receive the shaft 7. The framework also includes an inner bearing *b*, which supports the shaft 7 between the gears 15 and 18; and the right-hand standard *a* is provided with an extension *c*, in which is formed a bearing *c'*, to receive one end of the shaft 1. *c*² is a similar bearing in line with the bearing *c'* and made rigid with the framework by being connected to the standard *c* by means of an arm or bracket, or in any other convenient way. The framework in question also supports a circular ring *F*, which surrounds the rotary table 17 and serves as a sort of seat therefor, on Fig. 2.

As will be seen by reference to Fig. 1, the collar 14 is of the grooved type, providing means for the bifurcated end of a lever 21 to be operatively connected thereto, without preventing the rotation of the collar and the shaft relative to the lever. The lever may be pivoted intermediate its ends at 22, and is provided at its opposite ends with a pair of pins 23 and 24. Connected to the pin 23 in a slidingly pivoted manner, as by means of a slot 25, there is provided a connecting rod 26, which is connected at its opposite end by a similar pin-and-slot connection, to an arm 27 of a bell crank lever 28. Connected to the pin 24 by a slotted arrangement similar to that of the connection rod 26, there is provided a similar connecting rod 29, which extends to a position where it also is connected to an arm 30 of the bell crank lever 28, by means of a pin-and-slot connection, permitting a certain amount of relative motion. Inasmuch as the key 9 is to be operated by the lever 21, which in turn is operated by the rods 26 and 27, it is necessary to allow for the movement of the parts, in shifting from one position of the key to another, until such time as the key shall come opposite one of the grooves or recesses 11 or 12 while moving in the cavity 10. The lost motion provided by the pin-and-slot connection of the rods 26 and 29 to the lever 21 and the lever 28 allows for this action. There is also provided a spring 31, which is connected at its opposite ends to the rods 26 and 27. The length of the rods 26 and 29 may be adjusted in any suitable manner to the proper degree, as by means of turnbuckles 32 and 33.

Oscillatably mounted adjacent to the table 17 and projecting above the surface of the same, there is provided a trip 34, hav-

ing an arm 35 which projects horizontally at substantially right angles to the vertically-disposed body portion of the trip. This trip may be operatively connected in any well known manner to the bell crank lever 28, as by being provided with an arm 36 at its lower end, in which an opening 37 is provided, for the purpose of permitting a lug 38 on the bell crank lever 28 to have operative connections with the trip 34 at all times, irrespective of the vertical position of the trip; that is to say, this arrangement permits the trip 34 to be operated from the bell crank lever 28, and also to operate said bell crank lever, and yet permits of a vertical motion of the trip relative to the table. For the purpose of providing this vertical motion, the vertical shaft of the trip 34 is formed with a grooved collar 39, in a groove of which extends one end of a lever 40, pivotally connected at any point, such as 41, in any suitable manner. This lever is bifurcated also at its opposite end and extends into the groove of a similar collar 42 on a trip 43, which, similarly to the trip 34, extends in a vertically-extending opening in the table 17, and is capable of vertical movement and oscillatory movement relative to the table. This trip 43 also has an arm 44, which extends outwardly similarly to the arm 35. On the table 17, there is provided a tripper 45, which is shown in the form of a disk rotatably mounted on a stub shaft on the table, and is adapted to engage either one of the arms 35 or 44 on the trips 34 and 43 respectively when the latter are on a level with the disk 45. By reason of the connection of the trips through the medium of the lever 40, however, it will be seen that when one of the trips is up, the other is down. In order that when one of the trips 34 or 43 is rotated, or rather oscillated in one direction, the other trip will be simultaneously rotated, and also in order that when either one of the trips is oscillated, the bell crank lever 28 will be simultaneously oscillated, the trip 43 is provided with an arm 46 at its lower end, which is connected to the bell crank lever 28 at the same side of the pivot thereof as the lug 38, by means of a link 47. To afford a natural tendency of the trips 34 and 43 to occupy a normal relative position, there is provided a spring 48, which is connected to one side of the lever 40 at one end, and to a fixed bracket 49 at its other end.

For the purpose of causing a vertical movement of the trips, one of the collars on one of them, such as the collar 39 on the trip 34, is engaged by the end of a lever arm 50, which is rigidly connected to a spindle 50', mounted on the framework of the mechanism, and carries at its other end a fixed control arm 51, which is operated from the con-

trolling mechanism for the knitting mechanism, indicated at 52. This may be of any suitable character, such as an endless chain 53 having links of varying heights adapted to lift and permit the depression of a plurality of arms 54 which rest thereon. This chain may pass over a suitable sprocket wheel 64, which may be driven in any suitable manner, so as to be in synchronism with the knitting mechanism, as, for example, by means of a pawl and ratchet connection with the table 17. The particular drive, however, does not form a part of this invention, and any well known form may be used.

It will be understood that the knitting mechanism comprises any well-known combination of mechanical elements by means of which the needles are manipulated and controlled in the manner required to make plain and racking stitches; and these elements are operated in such a way as to cause the needles to make a racking stitch when the apparatus is running at low speed, and to make a plain stitch when running at high speed. The pawl and ratchet mechanism which may be employed to drive the pattern chain 53 is of course driven in synchronism with the controlling mechanism, so that by means of the chain the lever 50 may be lifted to increase the speed at the same time when the needles are caused to make the plain stitches, and allowed to sink to reduced speed at the same time when the needles are caused to make the coarse or racking stitches. It will be seen that the control arm 51 forms, with the lever 50, a bell crank lever, which will be oscillated when the arm 54 is raised and lowered.

Inasmuch as the pattern chain 53 has links of three different heights, and the medium height link moves the lever arm 50 the desired distance, it is necessary to allow for the highest link. For this purpose the lever 50 is broken at 150 into two parts, pivotally connected together and normally held in alinement by a spring 151. The overlapping portions of the lever 50 are prevented from moving too far relative to each other, by a pin and slot connection 152, indicated in Fig. 4. The collar 39 prevents the trip 34 from going too high by engaging a stop formed by the support or frame in which the trip is mounted, which is allowed for by the lever 50 "breaking."

The operation of the device will be readily understood when taken in connection with the above description. Assuming the parts in the position indicated in Figs. 1, 3 and 4, it will be seen that the trip 43 has its arm 44 projecting inwardly and at such a height that it will be engaged by the tripper 45, as it comes around, with the table 17 moving in the direction of the arrow in Fig. 1. When this tripper 45 hits the trip 43, as indicated in Fig. 4, it will swing the latter outward;

at the same time, through the connecting arms and links 46 and 47, will manipulate the bell crank lever 28 and swing the arm 35 of the trip 34 inwardly, so as to be in position to be operated by the tripper 45 at some predetermined future time, depending on the controlling chain 53, which at that time will cause the trip arm 35 to be on a level with the tripper disk 45. By throwing the trip 44 from the inwardly-projecting position indicated in Fig. 1, the bell crank lever 28 is oscillated toward the left, thus pushing on the connecting rod 26 through the arm 27, and pushing on the connecting rod 29 through the arm 30. If the key 9 should happen to be in a position in opposition to the groove 12, it would, by this movement, through the instrumentality of the lever 21, and the rod 13, be drawn into the groove 12, connecting the gear 8 in driving relation with the shaft 7. If, however, the gear should be in a position such that the key 9 was not directly opposed to the groove 12, the bell-crank lever 28, by pressing the rod or link 26 to the left, will tension the spring 31. It will be noted by reference to Fig. 1, that the rod or link 29 at this moment is in positive engagement with the pin 24 on the lever 21, but the pin carried by the arm 30 of the bell-crank lever 28 is at this time in the extreme right end of the slot. In consequence, the rotation of the bell-crank lever 28 to the left, or in a direction contrary to that of the hands of a clock, will not engage the rod 29 in such a way as to push it to the left along with the rod 26. The instant, however, that the gear 8 in the course of its rotation brings the recess 12 opposite the key 9, the spring 31, which, as before stated is now under tension, will pull the rod 29 to the left also, and the rod 29 will then act on the pin 24, moving the upper end of the lever 21 to the right, and thus draw the key 9 into the recess 12. This will of course lock the gear 8 to the shaft 7. It will thus be seen that when the arm 44 on the trip 43 was projecting inwardly, the drive from the shaft 1 to the shaft 7 was through the gear 4 and the gear 6, and that by this action of the tripper 45, the drive has been shifted to the interconnecting gears 5 and 8 between the shafts 1 and 7, so that the speed of the shaft 7 has been materially reduced. Inasmuch as the vertical position of the arm 44 is controlled from the knitting mechanism control 52, including the chain 53, this arm 44 will only be in position to be struck by the tripper 45 when it is desired to change from the rapid drive of the knitting mechanism corresponding to the close knitting of the sweater, to the slow drive of the knitting mechanism corresponding to the coarse knitting of the sweater.

When the machine changes from a slow

drive of the knitting mechanism, corresponding to the coarse knitting of the sweater, to the rapid drive, corresponding to the close knitting of the sweater, another part of the pattern chain will engage the arms 54 and cause the lever 50 to lift. As a result the trip 35 which has been previously rotated in toward the circle of revolution of the tripper 45, will be lifted to the level of this tripper 45, and it will be of course engaged by the tripper 45, as soon as the tripper reaches it, to be rotated outward or to the right, the same as the trip 43 in the preceding case. When the trip 35 is thrown outward in this way, the bell-crank lever will be rotated to the right. The rod 29 will then be pulled, tensioning the spring 31; and as soon as the recess 11 in the gear 6 comes opposite the key 9, the tension of this spring 31 will be sufficient to draw the rod 26 to the right also, swinging the lever 21 to the left at its upper end, which is contrary to its direction in the preceding case; and as a result the gear 6 will be locked with the shaft 7, and the fast drive will once more come into operation. It will thus be seen that the knitting mechanism represented by the elements 17 and 20 will be driven fast or slow, according to the type of stitch being knitted, and that the change from one to the other will be automatic and in synchronism with the change in the type of stitch.

While I have shown one embodiment of my invention, I do not wish to be limited to the specific details thereof, but desire to be protected in various changes, alterations and modifications which may come within the scope of the appended claims.

Having thus described my invention, I claim as new and desire to secure by Letters Patent:—

1. The combination with knitting-mechanism elements, of driving connections for said elements, knitting-mechanism controlling means for varying the stitch on the knitting-mechanism elements, and means for varying the speed of said driving connections in synchronism with the change of stitch brought about by said controlling means, comprising a plurality of trips operatively connected to said driving connections, a tripper for tripping said trips to change the speed of said driving connections, said trips being adjustable into and out of operative alinement with said tripper, and operative connections between said controlling means and said trips for adjusting the position of said trips from said controlling means.

2. The combination with a shaft, of a knitting table driven by said shaft, connections for changing the speed of said shaft, a trip for operating said connections, a trip 65 per mounted on said table, for actuating

said trip, and controlling means for varying the relative position of said trip with respect to said tripper.

3. The combination with a shaft, of knitting elements driven from said shaft, operative connections for changing the speed of said shaft, a plurality of trips for actuating said connections, a tripper connected with one of said elements and adapted to operate said trips, and controlling means for shifting any one of said trips into a position in which it will be operated by said tripper. 70 75

4. The combination with a shaft, of knitting elements driven from said shaft, operative connections for changing the speed of said shaft, a plurality of trips for actuating said connections, a tripper connected with one of said elements and adapted to operate said trips, controlling means for 80 85 shifting any one of said trips into a position in which it will be operated by said tripper, and operative connections between said trips for permitting only one of said trips to be in operable relation with respect 90 to said tripper at one time.

5. The combination with a drive shaft, of a driven shaft, knitting mechanism driven from said driven shaft, variable drive connections between said drive shaft and said driven shaft, shifting means for operating said connections so as to vary the speed of said driven shaft relative to said drive shaft, a lever for operating said shifting means, a pair of connecting rods having a lost-motion connection with said lever, a bell crank lever having an arm connected to each of said rods, a spring connected to said rods so as to take up any relative movement of said rods, and means for operating said bell 100 105 crank lever from said knitting mechanism.

6. The combination with a drive shaft, of a driven shaft, knitting mechanism driven from said driven shaft, variable drive connections between said drive shaft and said driven shaft, shifting means for operating said connections so as to vary the speed of said driven shaft relative to said drive shaft, a lever for operating said shifting means, a pair of connecting rods having a lost-motion connection with said lever, a bell crank lever having an arm connected to each of said rods, a spring connected to said rods so as to take up any relative movement of said rods, and means for operating said bell 110 115 120 125 crank lever from said knitting mechanism, comprising a trip connected to said bell crank lever, and a tripper moving with said knitting mechanism and adapted to actuate said trip.

7. The combination with a drive shaft, of a driven shaft, knitting mechanism driven from said driven shaft, variable drive connections between said drive shaft and said driven shaft, shifting means for operating 130

said connections so as to vary the speed of said driven shaft relative to said drive shaft, a lever for operating said shifting means, a pair of connecting rods having a lost-motion connection with said lever, a bell crank lever having an arm connected to each of said rods, a spring connected to said rods so as to take up any relative movement of said rods, and means for operating said bell crank lever from said knitting mechanism, comprising a trip connected to said bell crank lever, a tripper moving with said knitting mechanism and adapted to actuate said trip, and controlling means for said knitting mechanism, operative to control the operation of said trip by said tripper.

8. The combination with a shaft, of knitting mechanism driven by said shaft, a tripper actuated by said knitting mechanism, connections for varying the speed of said shaft, a plurality of trips for operating said connections, said trips being operated by said tripper, said trips being capable of vertical movement relative to said tripper, and means for connecting said trips together so as to move vertically simultaneously in opposite directions.

9. The combination with a shaft, of knitting mechanism driven by said shaft, a tripper actuated by said knitting mechanism, connections for varying the speed of said shaft, a plurality of trips for operating said connections, said trips being operated by said tripper, said trips being capable of vertical movement relative to said tripper, means for connecting said trips together so as to move vertically simultaneously in opposite directions, and means for moving said trips vertically.

40 10. The combination with a shaft, of knitting mechanism driven by said shaft, a tripper actuated by said knitting mechanism, connections for varying the speed of said shaft, a plurality of trips for operating said connections, said trips being operated by said tripper, each of said trips having an arm thereon adapted to be projected into the path of said tripper by an oscillatory motion of said trips, and means for connecting said trips together so as to simultaneously rotate in opposite directions.

11. The combination with a drive shaft, of a driven shaft, variable speed gearing for said shafts, knitting mechanism driven by said driven shaft, a lever for controlling the speed gearing, a plurality of rods, having loose connection with said lever, adapted to shift said lever, a spring connecting said rods, adapted to take up lost motion of the loose connection of said rods with said lever and means operated by said knitting mechanism for moving said rods so as to vary the speed of said driven shaft.

65 12. The combination with a shaft, of yarn-working means driven by said shaft,

means for changing the speed of said shaft, means for operating said speed-changing means to cause the shaft to be driven faster, means for operating the speed-changing means to cause the said shaft to be driven slower, means moving with said yarn-working means for actuating the said operating means to put them into and out of play, and controlling means for varying the relative position of said operating means with respect to said actuating means.

13. The combination with a shaft, of yarn-working means driven by said shaft, means for changing the speed of said shaft, means for operating said speed-changing means to cause the shaft to be driven faster, means for operating said speed-changing means to cause the shaft to be driven slower, means moving with said yarn-working means for actuating said operating means to put them into and out of play, and means for moving said operating means into and out of position to be engaged by said actuating means.

14. The combination with a shaft, of yarn-working mechanism driven thereby, means for changing the speed of said shaft, means for operating said speed-changing means for causing the shaft to be driven faster, means for operating said speed-changing means to cause the said shaft to be driven slower, means for connecting said operating means to move in unison, and means moving with said yarn-working means for actuating said operating means by turns, the connecting means between said operating means causing one of said operating means to be moved toward the actuating means when the other is moved away therefrom.

15. The combination with a shaft, of yarn-working mechanism driven by said shaft, means for changing the speed of said shaft, means for operating said speed-changing means to cause the shaft to rotate faster, means for operating said speed-changing means to cause said shaft to rotate slower, means moving with said yarn-working means for actuating said operating means, and controlling means for moving one or the other of said operating means into position to be engaged by said actuating means.

16. The combination with a shaft, of yarn-working mechanism driven by said shaft, means for changing the speed of said shaft, means for operating said speed-changing means to cause the shaft to rotate faster, means for operating said speed-changing means to cause said shaft to rotate slower, means moving with said yarn-working means for actuating said operating means, and controlling means for moving said operating means successively in opposite directions into position to engage the said actuating means.

17. The combination with a shaft, of

- yarn-working mechanism driven by said shaft, means for changing the speed of said shaft, means for operating said speed-changing means to cause the shaft to rotate faster, 5 means for operating said speed-changing means to cause the shaft to rotate slower, means for connecting said operating means, means moving with said yarn-working mechanism for actuating said operating means, the connecting means between the 10 said operating means, causing one of said operating means to be moved toward the actuating means and the other to be moved away therefrom whenever one of said operating means is engaged by the actuating means, and controlling means for moving said operating means by turns into position to be engaged by the actuating means. 15 18. The combination with a shaft, of 20 yarn-working mechanism driven thereby, means for changing the speed of said shaft, a link for operating the speed-changing means to cause the shaft to move faster, said link having lost-motion connection with the 25 speed-changing means, another link for operating the speed-changing means to cause the shaft to move slower, the said other link also having a lost-motion connection with the speed-changing means, means for actuating 30 said links having lost-motion connection with the same, and means moving with said yarn-working mechanism to actuate the last-mentioned means. 19. The combination with a shaft, of
- yarn-working mechanism driven thereby, 35 means for changing the speed of said shaft, a pair of links for operating said speed-changing means and having a lost-motion connection therewith, means for operating said links and having lost-motion connection with the same, resilient means for connecting said links together, and means moving in said yarn-working mechanism for actuating said operating means. 40 20. The combination with a shaft, of 45 yarn-working mechanism driven by said shaft, means for changing the speed of said shaft, a pair of links for operating said means and having lost-motion connection therewith, means for operating said links 50 to move the speed-changing means to cause the shaft to rotate faster, means for operating said links to cause the said shaft to rotate slower, said operating means being connected together, actuating means moving with the yarn-working mechanism to engage said operating means, and controlling means for moving said operating means by turns into position to be engaged by said actuating means. 55 60 In testimony whereof I have signed my name to this specification in the presence of two subscribing witnesses.
